O. H. Brooks

Washing Machine,

Patented Mar 11 1833

May 11, 1883

(Oliver H. Brooks' washing machine)

Letters Patent

The object of this invention is to have a Patent Patent and making
use of the same containing a description in the name of Oliver H. Brooks
of Boston, himself of his improvement in the following described claim:

To all to whom these presents shall come

Be it known that I, Oliver H. Brooks of Boston in the County of Boston
(and State of Massachusetts) have invented a new and useful improvement in a Washing
Machine used for washing clothes and other laundry articles & like machine
used for cleaning clothes into better. What the following is a full & exact
description of the construction & operation of the said machine called the
family washer as invented or improved by me, the particular. First a wooden
box chest or box made of heavy strong lumber having about twenty four
inches long & fourteen & a half inches wide made near the bottom of about eight
inches high the upper part of one end sloping outward and raised
expensive for a wash board, the bottom hollowed out between the end up
on a curve gradually a radius of about five feet. Secondly two double head
ed hammers or blocks of wood about eighteen inches long & six inches wide
& eighteen inches thick notches at each end much like the hammers
in a common fulling mill, on to each hammer is fastened a board about
four feet long, these boards wide & one & a half inch thicker by which board
the said hammers are hung in said chest about one foot apart from
the bottom by means of a large pin passing thru perpendicular posts fasten
ed upon the centre of the two ends of the chest & the upper ends of the
hammers. Thirdly a staff about twenty inches long & three inches in diameter, this
staff being rotatally arranged & about seven inches above the end of the chest, that is perpendicular
to it is supported in its bearing by two posts attached to the chest, one end of
said staff coming out about four inches further than the side of the chest &
the other end being firmly fastened two arms about seven inches long & two & a
half inches square are suspended from this staff & the other end of the same arms
extending them outwards about two feet long, made of light wood & half inch

1910 A

thick, extending from the arms to the hammer handles, forming their long portions over the ends of the arms & like mortises in the hammer handles horizontal with the shaft. & from just below the arms & reaches but six & a half inches from the center of the shaft. & from thence the hammer handles reach horizontal with the center of said shaft in such a manner that the reaches may turn or play on the mortises so far as to let the hammer swing or vibrate from one end of the chest to the other & at such distance that while one hammer hits at one end the other hammer shall hit at the other end long enough either way.

^{Perfectly} Two round levers about two & a half feet long & one & a fourth inch in diameter, one end of each firmly fastened into each side of the shaft nearly horizontal, the one over the centre & the other over the prominent end.

The machine being made principally of wood & put together with nails & screws. The manner of putting the machine in motion is by applying power by hand or otherwise to one or both levers & causing them to vibrate up & down at the same time it causes the hammers to vibrate in the chest. The manner of using the machine for washing is to put clothes & other articles into each end of the chest & warm water or suds. By putting the machine in motion it will cause the clothes to be beat, squeezed, rolled over, & washed very fast, & the manner of using the machine for churning cream into butter, is to use a machine of some top dimensions with a cover, by putting the cream into the chest & letting the machine in motion. That part of the above described machine which I claim as the inventor or discover or applying the two double-headed hammers, to the use of firmly working & churning cream into butter, & the manner of putting them in motion by means of the shaft, arms, reaches & levers, as above described. Preference is to a drawing heretofore deposited in the Patent Office.
